ABSTRACT: This is an electronic circuit which is useful particularly in establishing for vehicles a backup warning. The circuit is adapted to input voltages ranging from 6 to 36 volts of either polarity and wherein the output voltage can be varied to develop a given desired regulated voltage for actuating a warning device. The circuit comprises basically a bridge section, a capacitor section, a regulator section and speaker and may include oscillator, flip-flop, and amplifier.

VEHICLE ELECTRONIC BACKUP WARNING DEVICE

BACKGROUND OF THE INVENTION

In the present system, which is solid state, there is less vulnerability to malfunction than in the art because of a total lack of moving parts, contacts or bushings which may be subject to wear; there are no springs changing tension, no adjustments, no cams as are currently known in reverse alarms of the prior art.

Moreover, as opposed to art, polarity and voltage are protected and the system is universally adapted to substantially any vehicle on the market today.

Known prior art is as follows:

Knutson	2,972,139
Knutson	3,076,960
Webster	2,870,428
Atkinson	2,940,063
Brett	2,829,213

With the exception of Atkinson, none of the known prior art includes a solid-state electronic media, nor have any of the known systems been adapted to either 6, 12, 24, 32, or 36 volt input source. Not only is the present system readily physically mounted on existing equipment, but it is operative at extreme temperature ranges and can be cleaned without damaging. With the exception of Atkinson, the life expectancy is indefinite, polarity and voltage are each protected, the device is explosionproof and vibrationproof, and the proper sound level herein can be concentrated in the hazard zone only of the vehicle.

SUMMARY OF THE INVENTION

The invention relates to circuit for reduction of voltage from a range to a given desired voltage. While the circuit is usable with input voltages ranging from 6 to 36 volts of either polarity, it operates in one preferred form to produce an 8.2-volt output, but the output can be varied in any desired voltage by the incorporation of appropriate regulator components therein. The circuit includes a first station (bridge) to establish a fixed polarity for subsequent sections or stages. In the second stage (capacitor section), means are operable to filter out peak voltages and foreign signals. In the third stage (regulator section), the components are operable to reduce voltages of different values within a given range, down to the desired output voltage and, as required, oscillator, flip-flop, amplifier sections are added sequentially prior to actuation of the speaker. The on-off control may be a magnetic proximity switch actuatable by gearshift lever and having conductive switch connection between vehicular battery and electronic capsule containing the actuating circuitry mentioned.

BRIEF DESCRIPTION OF THE DRAWING

The FIGURE is a view of the preferred circuit in the present invention.

As indicated, the entire actuating circuitry is adapted to a capsule attached to the speaker alarm itself. To energize the circuit, one may adapt the electronic actuating capsule input to battery, interrupted at selection by a magnetic proximity switch of the type mounted on a gearshift lever and adjacent mount including magnetic tube on the lever and switch tube on the mount.

DESCRIPTION OF THE PREFERRED EMBODIMENTS

With reference to the drawing, in the first section, the bridge B1 has a value of FW-100 and is adapted to establish a fixed polarity to the sequential sections. Input to the bridge may be at either 6, 12, 24, or 32 or 36 volts, negative or positive ground, thus making it universal for the majority of domestic vehicles. In this way, the system can be shifted without regard to voltage or polarity from one vehicle to another. Moreover, if the present system is installed on a 12-volt negative to ground unit and the battery of the vehicle is

dead, subsequently boosted but the polarity erroneously reversed, the system would not be damaged, and the same would be true if a dead battery is erroneously replaced in reverse polarity in the vehicle on which the unit is mounted. The entire circuitry herein is solid state, thus eliminating wearing, sparking, or the necessity for lubrication of parts.

In the second section, the capacitor C4 is adapted to filter out spike voltages and undesirable foreign signals, capacitor C4 having a value in this instance of 250 mf.

10 In the third or regulator section which comprises basically transistor T2, the transistor is Model 2N4995 manufactured by Texas Instrument. Here by resistance R11 and zener diode Z1, all voltages are reduced from 6 to 36 down to trigger at 8.2 volts.

15 This voltage regulation, regardless of polarity, permits adaptation of the system to any vehicle, regardless of its inherent voltage system. Within the regulator system the zener diode Z1 having a value represented by Semicor parts No. IN3018B; the Ohmite resistor R11 having a value of 1 kΩ ½ w.

20 which is the same value given the resistors R3 and R8 in the oscillator circuit shown.

The oscillator circuit converts the uniform regulated voltage into a signal of 900-1,200 cycles per second, also includes Mallory capacitors C1, each of a 0.1 mf. and within that circuit there are also the IR diode D1 of IR Part No. 20A05. The Ohmite resistor R1 is of 56 Ω ½ w., the Ohmite resistor R2, 6.8 kΩ ½ w., the Ohmite resistor R10 of 510 Ω ½ w. Ohmite resistor R9 is given a value of 8.2 kΩ ½ w. The Texas Instrument transistors T2 are identified as 2N4995.

30 In the flip-flop circuit the signal transmitted by the oscillator is pulsated at the desired rate of 1 pulse per second, whereupon it is appropriately switched via transistor and amplified to the speaker.

35 Values given the elements in the flip-flop circuit are for the Resistor R5, 39 kΩ ½ w.; for the resistor R7, 68 Ω ½ w. Capacitor C2 has a value of 10 mf. and C3 a value of 20 mf. Resistances R4 and R6 are of the same value as resistances R3 and R8 in the oscillator circuit.

40 The transistor T1 in the amplifier circuit is a Semicor SDT 9603 and the speaker S1 is identified as a 16 Ω 1 MP Atlas speaker.

Fine points A and B are respectively positive and negative, as shown.

45 I claim:

1. In a vehicle back-up warning device, a circuit for providing uniform voltage, switched signals comprising:
  - A. an electrical power source;
  - B. a bridge circuit section arranged to provide a fixed polarity having across said bridge a capacitor in parallel with a voltage-reducing regulator circuit comprising at least one transistor arranged to regulate the voltage at a consistent potential at the output of said bridge;
  - C. an oscillator circuit in series to said bridge circuit and said voltage reducing regulator circuit sections to develop particular frequencies;
  - D. a flip-flop circuit arranged in parallel with said oscillator circuit;
  - E. an amplifier arranged at the output of said oscillator and said flip-flop circuits; and
  - F. warning means in parallel to said amplifier, oscillator, flip-flop, and voltage-reducing regulator circuits.

60 2. The system according to claim 1 in which oscillating section includes plural transistors, all said transistors being of equal value.

65 3. The system of claim 2 in which the said flip-flop circuit includes plural transistors, all said transistors being of equivalent value.

70 4. The system of claim 3 wherein the oscillator circuit converts uniform electrical voltage to a signal of at least 900-1,200 cycles per second frequency.

75 5. The system of claim 2 in which the input voltages may vary from 6-36 volts and wherein the voltage reduction section reduces the input voltages to 8.2 volts.

6. The system according to claim 4 in which the input voltages may vary from 6-36 volts and wherein the voltage reduction section reduces the input voltages to 8.2 volts.

UNITED STATES PATENT OFFICE
CERTIFICATE OF CORRECTION

Patent No. 3,629,819

Dated December 21, 1971

Inventor(s) Edwin R. Peterson

It is certified that error appears in the above-identified patent and that said Letters Patent are hereby corrected as shown below: On drawings (Fig. 1 and drawing page 1) a connection should be indicated at the intersection connecting the upper right transistor to diode D1, resistor R9, and the lower capacitor C1; a connecting line should be drawn between the base of the lower left transistor and the top of resistor R5; the connecting point labelled A on the bottom horizontal line between R5 and R7 should be labelled C. A connecting point C should be applied on the top horizontal line between R2 and R9; the right-hand transistor should be identified T1.

In the Specification:

Column 1, line 40, change "station" to -- stage --.
Column 2, line 8, change "pike" to -- spike --; line 25, delete "56", insert -- 510 --; line 26, delete "510", insert -- 56 --; line 34 delete "68", insert -- 68K --; line 59, delete first "said".

Signed and sealed this 19th day of February 1974.
